TALKING PICTURE APPARATUS

Filed June 13, 1927

INVENTOR.

Freeman H. Owens,
BY
John B. Brody
ATTORNEY.

UNITED STATES PATENT OFFICE

FREEMAN H. OWENS, OF NEW YORK, N. Y.

TALKING-PICTURE APPARATUS

Application filed June 13, 1927. Serial No. 198,648.

My invention relates broadly to talking picture apparatus and more particularly to a construction of mounting for the light source used in a talking picture projecting system.

One of the objects of my invention is to provide a construction of housing for a light source in a talking picture projecting system.

10 Another object of my invention is to provide a housing for the lamp source of a talking picture projecting system which lamp housing may be mounted immediately adjacent the motion picture projecting machine 15 for controlling the talking picture light source from a position immediately adjacent the controls of the motion picture projecting apparatus.

Still another object of my invention is 20 to provide a construction of lamp housing and control equipment for the light source of a talking picture system wherein the control equipment for mounting upon a swinging panel member which forms part of the housing for the light source for permitting access to be had to the light source for adjustment without interference with the controls adjacent the light source.

Other and further objects of my invention 25 will be understood from the specification hereinafter following by reference to the accompanying drawings, in which:

Figure 1 is a front elevation of the control panel on the lamp housing of my invention; 30 Fig. 2 is a cross-sectional view through the lamp housing showing the interior of the housing; Fig. 3 is a vertical cross-sectional view through the housing on line 3-3 of Fig. 2 illustrating the assembly of the controls within the housing and Fig. 4 illustrates 35 the position of the control panel with respect to the lamp housing when the lamp housing is opened for adjustment of the light source.

40 In talking picture systems, it is necessary to accurately control the intensity of the light source and adjustment of the position of the light source may be required from time to time. My invention is directed to a 45 housing for the light source, wherein the

controls are mounted on a panel immediately adjacent the light source and the panel provides one wall of the housing which encloses the light source. The panel is right angular in cross-section and may be swung 55 to a position remote from the light source opening the housing to permit access to be had to the adjustable mounting for the light source. I employ in the lamp housing of my invention, a mounting for the light source 60 constructed in accordance with my Patent No. 1,735,834, Nov. 12, 1929. The assembly of the control equipment and the construction of the lamp housing is such that a minimum space is required for the installation 65 of the lamp housing. In installing the lamp housing on picture projecting machines, the housing may be vertically positioned with respect to the projecting machine and readily accessible to the operator. 70

Referring to the drawings in more detail, reference character 1 designates a vertical wall structure on which the parts of the control equipment and the light source are mounted. Reference character 2 designates a 75 wall member projecting at right angles from rear wall 1. The condensing lens system for the sound picture projection apparatus is represented at 3 within tubular member 4 which is arranged adjacent a light aperture 80 in the wall 2. The lamp housing has bottom member 5 forming a lower closure for the housing. The adjustable lamp holder is mounted from a bracket 6 on rear wall 1 and includes the supporting block 7 and socket 85 member 8 for receiving the lamp 9. The various adjustments which are permitted for the lamp source have been clearly set forth in my patent to which reference is made for a more detailed disclosure of the light source. 90 The controls for the light source are mounted upon the swinging panel structure represented at 10 and 11 as pivotally mounted at 19 to the rear wall 1. The panel 11 provides a support for the ammeter 12, the variable 95 control rheostat 13 and switch member 15. The rheostat 13 is controlled from the front of the panel by means of control knob 14. Switch member 15 may be snapped on or off 100 from the front of the panel 11 by means of

control knob 16. The panel is moved outwardly or returned to closed position by means of knob 17 which may control the latch 18 which engages the wall 2 for securing the panel 11 in closed position with respect to the wall member 2. By reason of the fact that both the front panel 11 and side wall panel 10 may be substantially removed from the light source mounting, sufficient working space is obtained for effecting the required adjustments within the lamp housing. The leads from a series circuit are shown including ammeter 12, control rheostat 13, switch 15 and the terminals of the light source 9 extend outside of the lamp housing to a suitable power source. Sufficient flexibility and slack may remain in the leads to allow the free movement of the swinging panel from a position entirely enclosing the light source 9 to a position remote from the light source 9. The alignment of the light source 9 with the condensing lens system and light slit in the sound picture projecting system, may be readily secured by adjustment of the block 7 with respect to the supporting bracket 6.

The construction of lamp housing and control panel of my invention has been found to be extremely practical in picture projecting systems and while I have described a preferred embodiment of the invention, I desire that it be understood that modifications may be made and that no limitations are intended other than are imposed by the scope of the appended claims.

What I claim as new and desire to secure by Letters Patent of the United States is as follows:

1. A lamp housing for talking picture projecting machines comprising a box like structure having a plurality of side walls two of which are integrally connected and hingedly attached to a third side permitting two complete sides of said structure to be swingingly moved together with respect to the other sides for easy access to the inside of the housing, an adjustable support for a light source, a lens system at one side of said lamp housing to which said light source is aligned and electrical instruments carried by one of the integrally connected side walls of said box like structure for governing and observing the operation of said light source.

2. A lamp housing for talking picture projecting machines comprising a box like structure having four side walls, top and bottom walls, two of said side walls being fastened together and swingingly mounted on a third side wall to permit easy access to the inside of said housing, an adjustable light source mounted on said third side wall, a lens system aligned with said light source and mounted on the fourth side wall, and instruments mounted on one of the said swingingly

mounted side walls for governing and observing the operation of said light source.

3. A lamp housing for talking picture projecting machines comprising a pair of wall portions disposed substantially at right angles to each other, each of said wall portions consisting of two side walls, an adjustable light source supported from one of said wall portions, a lens system positioned in alignment with said light source and carried by the other of said wall portions and a right angularly disposed wall portion pivotally mounted with respect to said first mentioned wall portion, permitting two of the side walls of said housing to be moved together with respect to the other two side walls for easy access to the interior of said housing, said right angularly disposed wall portion carrying control equipment on the interior wall thereof for governing the operation of said light source.

In testimony whereof I affix my signature.
FREEMAN H. OWENS.
